UNITED STATES PATENT OFFICE.

FREDERICK DIEHL, OF ELIZABETH, NEW JERSEY, ASSIGNOR TO THE SINGER MANUFACTURING COMPANY, OF ELIZABETH, NEW JERSEY, A CORPORATION OF NEW JERSEY.

LIGHTING DEVICE FOR SEWING MACHINES.

Application filed January 23, 1922. Serial No. 531,029.

To all whom it may concern:

Be it known that I, FREDERICK DIEHL, a citizen of the United States, residing at Elizabeth, in the county of Union and State 5 of New Jersey, have invented certain new and useful Improvements in Lighting Devices for Sewing Machines, of which the following is a specification, reference being had therein to the accompanying drawings.

10 Electric lighting devices for sewing machines, particularly when applied to machines operating at high speed, are subjected to a type of vibration which has a tendency to shorten the life of the lamp filaments.

15 The vibration of the machine frame is of small amplitude but is sometimes of a severe, sharp, or jarring character, in the nature of a rapid succession of hammer blows. While, by mounting the lighting device adjacent 20 the bend of the sewing machine gooseneck, the destructive effect of this vibration on the lamp-filament is sufficiently reduced to permit the attainment of a satisfactory life by lamp-bulbs having filaments of the more 25 rugged types, such as carbon or the metalized filaments, it is an object of the present invention to further reduce the vibration transmitted to the lamp-filament, or soften its character, in order that a satisfactory 30 life may be attained by lamps having filaments of the more delicate types, such as tungsten filaments.

Another object of the invention is to reduce the vibration of the lamp-filament in a 35 sewing machine lighting device retaining the advantages of the constructions disclosed in the copending applications of Frederick Diehl, Serial No. 449,968, filed March 5, 1921, and Serial No. 453,786, filed 40 March 19, 1921, among which advantages may be mentioned the ease with which the device may be applied to the machine; its effective illumination of the work; its neat and attractive appearance; the absence of 45 objectionable shadows on the work; the freedom from objectionable heat and glare and the freedom from interference with the dropping of the sewing machine head within the cavity of the usual drop-head cabinet, or 50 with the placing over the machine of the cover of the usual hand-carrying case.

To the attainment of the ends in view, a cushioning device is interposed between the horizontally disposed lamp-socket, which

carries the lamp-bulb and reflector, and the 55 sewing machine gooseneck. The cushioning device should be of compact or condensed form so that the lamp-socket may be sustained closely adjacent the point of connection of the device to the gooseneck. In the 60 embodiment of the invention illustrated, the cushioning device is in the form of a spring which may be plaited to reduce it to a condensed or compacted form. The lamp-socket 65 may be secured in a horizontal position to one end of the plaited spring which may be secured at its other end to a support rigid with the sewing machine frame. The spring is preferably made from a strip of spring 70 steel plaited or folded back-and-forth upon itself to reduce its length without a sacrifice of spring action and thus permit the lamp to be located close to its support and between the standard or vertical member of the gooseneck and the needle-bar head at the 75 free end of the gooseneck, whereby the light may fall obliquely upon the work from a position closely in rear of the middle portion of the overhanging arm, as provided for in said Diehl copending applications. The 80 plies or parallel sections of the plaited spring are preferably apertured to admit the conductor-cord. The reflector may be weighted, if desired, to increase the inertia 85 of the floating parts and still further steady the device.

In the accompanying drawings, Fig. 1 is a perspective view of the lighting device as applied to a portable sewing machine. Fig. 2 is a fragmentary top plan view of the attachment shown in Fig. 1. Fig. 3 is a rear side elevation of the attachment. Fig. 4 is an end view. Fig. 5 is a vertical section on an enlarged scale. Fig. 6 is a similar view with certain parts shown in Fig. 5 omitted. Fig. 6^a is a section on the line 6^a—6^a, Fig. 6. Fig. 7 is a top plan view of the invention embodying a modified form of support. Fig. 8 is a vertical sectional view of the device shown in Fig. 7. Fig. 9 is a transverse 90 vertical section on the line 9—9, Fig. 7, and Fig. 10 is a detail view of the free end of the support.

In the accompanying drawings, a sewing machine head of usual construction is illustrated in Fig. 1 as mounted upon a portable base 1. The sewing machine frame comprises a flat-bed 2 from which rises the hol-

low gooseneck or bracket-arm including the standard 3 and horizontal member or overhanging arm 3' terminating in the head 4 in which are slidably mounted the usual 5 presser-bar 5 and reciprocating needle-bar 6 carrying, respectively, the presser-foot 7 and needle 8. Cooperating with the presser-foot 7 to feed the work is the usual feed-dog 9. The needle 8 cooperates with the usual loop-taker below the bed 2 to form stitches. Machines of this type are usually driven by a suitable motor attachment which has been omitted from the illustration since it forms no part of the present invention. The sewing 10 machine may, of course, be supported and driven in any desired manner.

The hollow gooseneck or bracket-arm 3, 3' of a sewing machine of the type referred to, is usually provided with an opening 10 20 affording access to the working parts mounted within the arm. This opening is customarily located at the rearward side of the gooseneck, substantially at the bend of the latter.

25 The present lighting device, in the form shown in Figs. 1 to 6, inclusive, comprises a support in the form of a cover-plate 11 shaped to close the opening 10 and formed with an upper screw-hole to admit the usual 30 cover-plate thumb-screw 12. The cover-plate 11 is preferably formed with a projection in the form of an integral ear 13 bent rearwardly so as to stand in a vertical plane transverse to the plane of the plate 11 35 proper. Secured to the ear 13, as by screws 14, are the parallel plies 15 and 16 of a cantilever spring 17 of compact form, preferably constructed from a strip of spring steel bent back and forth on itself or plaited to form 40 a series of parallel plies, to the end ply 18 of which is secured the lamp-socket 19. The end ply 18 is preferably apertured to admit the nipple 20 which is screwed into the socket 19 and is formed with a head 21 45 which clamps the end ply 18 tightly against the end of the socket 19. The remaining plies of the spring are preferably apertured to freely admit the conductor-cord 22 which passes through the spring 17 without binding 50 or rubbing against the plies of the latter. An insulating bushing 23 is preferably fitted to the ear 13 and the plies 15 and 16 which are rigidly connected to such ear. Cushioning washers 24 of felt or other suitable 55 material may be interposed between the plies of the spring 17 to damp the relatively slow periodic vibration of the lamp which may be occasioned by contact of the operator's hand therewith, as in turning the light 60 on or off. The use of the damping expedient or washers is not essential, however, and they may be omitted, as illustrated in Fig. 6.

The transverse or horizontal resiliency of the spring 17 may be augmented by reducing the lengths of the fold lines between the

parallel plies, as by cutting away the ends of such folds at 17'.

The socket 19 receives the lamp-bulb 25, preferably of the tubular or cylindrical type, and supports a suitable reflector 26 70 which may be weighted, as at 27, to increase the inertia of the floating parts.

The cover-plate 11 may be formed with a lug 11' adapted to externally engage the rim of the aperture 10 and prevent sagging 75 of the lamp and cover-plate.

In the form of the invention illustrated in Figs. 7 to 10, inclusive, the lighting device includes a support 28 in the form of an elbow which is preferably fixed within an 80 apertured boss 29 adjacent the bend at the juncture of the standard 30 and overhanging arm 30' of the gooseneck of a machine of the type disclosed in the patent to Dosch et al., No. 1,311,114 and embodying a built-in motor 31 having its shaft 32 arranged transversely of and geared to the main-shaft 33 of the machine. The free end of the elbow 28 is slotted at 34 to receive the forked end ply 35 of a spring 36 of condensed form, 90 the construction being otherwise substantially the same as the spring 17 previously described. The screw 37 serves to secure the end ply of the spring in the slot 34 of the elbow support. The socket 19 and associated parts may be secured to the free end of the spring 36 in the same manner as they are secured to the spring 18; such spring operating to secure substantially the same results whether carried by the cover-plate 11 or 100 the elbow 28.

It will be observed that by the means described the lamp is yieldingly supported by a compact cushioning connection with the sewing machine gooseneck adjacent the 105 bend of the latter and is not displaced from its horizontal position closely in rear of and alongside the horizontal arm member of the gooseneck and between the needle-bar head and the vertical member of the gooseneck. 110 Thus, the advantages flowing from the novel position of the lamp, disclosed in said co-pending applications, are retained and vibration is reduced to the vanishing point by retaining the supporting connection with the sewing machine frame adjacent the bend of the gooseneck and by introducing a cushioning or yielding connection between the lamp-socket and its support. The light 115 from the lamp 25 will thus fall obliquely upon the work from the operator's right and will illuminate that edge of the presser-foot relative to which the edge of the work is customarily guided.

The described disposition of the light 125 avoids the casting of objectionable shadows upon the work by machine parts carried by or forming a part of the sewing machine bracket-arm. The lamp will not be subjected to the pounding vibration of the sew- 130

ing machine as the cushioning device interposed between the lamp-socket 19 and the sewing machine frame will absorb or soften the character of such vibration thus permitting the attainment of a satisfactory life by lamps having filaments of the more delicate types, such as tungsten. The compact form of the cushioning device is such that it is not necessary to space the socket a material distance from the point of support of the device on the sewing machine frame. The favorable location of the lamp in permanent working relation with the bracket-arm and within the vertical planes defined by the side and end edges of the sewing machine bed may thus be retained and the lighting attachment will not interfere with the dropping of the head within the cavity of the usual drop-head cabinet or with the placing of the cover of a hand-carrying case over the sewing head.

The lighting device may, of course, be applied to sewing machines having frames of any of the usual forms.

Having thus set forth the nature of the invention, what I claim herein is—

1. A sewing machine lighting device comprising a support adapted for attachment to a sewing machine gooseneck, a plaited spring secured at one end to said support, and an electric lamp-socket carried hori-

zontally at the other end of said plaited spring closely adjacent said support.

2. A sewing machine lighting device comprising a support adapted for attachment to a sewing machine gooseneck, a plaited spring secured at one end to said support, and an electric lamp-socket carried horizontally at the other end of said plaited spring closely adjacent said support, the width of the spring being reduced at the fold lines.

3. A sewing machine lighting device comprising a support adapted for attachment to a sewing machine gooseneck, a plaited spring secured at one end to said support, an electric lamp-socket carried horizontally at the other end of said plaited spring closely adjacent said support, and damping means interposed between the plies of said plaited spring.

4. A sewing machine lighting device comprising a support adapted for attachment to a sewing machine gooseneck, a spring device connected to said support, a horizontally disposed lamp-socket, reflector and lamp carried by said spring device and a weight carried at the free end of said reflector.

In testimony whereof, I have signed my name to this specification.

FREDERICK DIEHL.
